UNITED STATES PATENT OFFICE

155,025

DESIGN FOR A COMBINATION BABY WALKER AND STROLLER

Frank S. Nanna, North Lake Village, Ill.

Application October 5, 1948, Serial No. 148,971

Term of patent 7 years

(Cl. D14—3)

To all whom it may concern:

Be it known that I, Frank S. Nanna, a citizen of the United States, residing in North Lake Village, in the county of Cook and State of Illinois, have invented a new, original, and ornamental Design for a Combination Baby Walker and Stroller, of which the following is a specification, reference being had to the accompanying drawings, forming part thereof, in which:

Fig. 1 is a side elevational view of a combination baby walker and stroller embodying my new design; the opposite side of the design being substantially similar in appearance;

Fig. 2 is a top plan view of the combination baby walker and stroller shown in Fig. 1;

Fig. 3 is a front elevational view of the combination baby walker and stroller; and

Fig. 4 is a rear elevational view of same.

I claim:

The ornamental design for a combination baby walker and stroller, substantially as shown and described.

FRANK S. NANNA.
